UNITED STATES PATENT OFFICE

2,530,095

STOVE ATTACHMENT

Curtis T. Stevens, St. Simons Island, Ga.

Application June 14, 1946, Serial No. 676,654

1 Claim. (Cl. 138—45)

1

This invention relates to an attachment for coal burning stoves and is especially intended to provide an attachment of simple construction by means of which a sheet metal wood burning stove may be readily converted into a coal burning stove, but is likewise well adapted for stoves constructed for use as coal burners and may be embodied therein as a part of a stove as originally constructed or may be applied thereto as an attachment for stoves already in use.

It is a primary object of the present invention to provide an attachment for admitting air to the fuel of a coal burning stove in such a manner that the grate will not be oxidized thereby but nevertheless so that the air will be discharged into the coal so as to result in maximum combustion.

A further object of the invention is to provide air supply means adapted to be located in the fire bed and adjacent the grate of a stove to concentrate the flame and the burning portion of the fuel bed adjacent the center of the grate to thus enable the burning of coal in sheet metal stoves, intended as wood burning stoves.

Other objects and advantages of the invention will hereinafter become more fully apparent from the following description of the drawings, which illustrate a preferred embodiment thereof, and wherein:

Figure 1 is a front elevational view of a stove with the attachment, comprising the invention, applied thereto;

Figure 2 is a vertical sectional view of the stove taken substantially along a plane as indicated by the line 2—2 of Figure 1;

Figure 3 is an enlarged transverse vertical sectional view of a portion of the stove taken substantially along a plane as indicated by the line 3—3 of Figure 2;

Figure 4 is a longitudinal, substantially central sectional view showing the attachment removed;

Figure 5 is a cross-sectional view of the attachment taken substantially along a plane as indicated by the line 5—5 of Figure 4, and

Figure 6 is a fragmentary horizontal sectional view thereof taken substantially along a plane as indicated by the line 6—6 of Figure 5.

Referring more specifically to the drawings, the numeral 7 generally designates a heating stove having depending supporting legs 8 and a removable top 9. The top wall 9 of the stove is provided with an opening 10 equipped with a swingably mounted closure 11 through which fuel is applied to the stove. The opening 10 is

located adjacent the front part of the stove and the top wall 9 is provided with a flanged opening 12, adjacent the rear of the stove, which is connected to a stack or chimney 13. The stove 7 may be of any desired shape and is provided in the front part and adjacent the bottom thereof with a flanged opening 14 containing a removable closure 15. The flange opening 14 is provided for removal of ashes from the bottom portion or 10 ash pit 16 of the stove 7. The side walls 17 and bottom 18 of the stove 7 may be formed of sheet metal, as is conventional in wood burning stoves or may be formed of cast iron or other heavier material. The top wall 9 is preferably formed 15 of cast iron to withstand the heat to which the top wall is subjected.

A grate 19, having a concave upper side is mounted in the lower portion of the stove casing and is supported above the bottom 18 by depending legs 20 which rest on the upper side of the bottom 18.

The front portion of the stove wall 17 is provided with an opening 21 which is located above and adjacent to the flange opening 14 for receiving a pipe or conduit 22 which is disposed with a substantial portion thereof located in the stove 7 and above and adjacent to the upper, concave side of the grate 19. The pipe or conduit 22 is provided adjacent its outer end with a collar 23 which is secured by fastenings 24 to the outer side of the stove wall 17, around the opening 21. The inner portion of the pipe 22, which is located above the grate 19, is provided with two longitudinally extending rows of apertures 25 which open outwardly and obliquely downwardly with respect to the grate 19, as best illustrated in Figure 3.

The pipe 22 is provided, adjacent its outer end and outwardly of the collar 23, with an arcuate slot 26 of a length in excess of 180 degrees. The pipe 22 is provided with an upwardly projecting apertured ear 27 located adjacent one end of the slot 26 for receiving a fastening 28 which extends through and pivotally engages an arm 29 which 40 projects from a portion of a valve 30. The valve 30 is substantially circular and of a diameter substantially equal to the internal diameter of the pipe 22 and is provided with a cut-away portion 31. The valve 30 is provided with a handle 32 45 which projects therefrom through the slot 26 and which is disposed substantially in diametrically opposed relationship to the arm 29. It will be readily apparent that by swinging the handle 32 in a counter-clockwise direction as seen in Figure 5, that the valve 30 will be swung upwardly

and outwardly with the respect to the slot 26 and the bore of the pipe 22 to thereby increase the size of the passage of the bore of the pipe 22 adjacent to the valve 30. The fastening 28 is adapted to be tightened sufficiently so that it will frictionally engage the arm 29 to retain the valve 30 in an open or partially open position. As seen in Figure 5, when the valve 30 is in a fully closed position the cut-away portion 31 will form a restricted passage with a part of the bore of the pipe 22 to allow a limited amount of air to pass inwardly through the pipe or conduit 22, so that the valve 30 is not capable of entirely shutting off the passage of air therethrough.

From the foregoing it will be readily apparent that the apertured portion of the pipe or conduit 22 is disposed just above the concave upper side of the grate 19 so that when coal, not shown, is supported on the grate and ignited the coal and bed of burning embers will be located over and around the apertured portion of the pipe 22. The smoke stack or chimney 13 in carrying off the product of combustion from the stove 7 will cause a partial vacuum to be created therein which will create a suction in the pipe 22 so that air will be drawn inwardly through the outer open end 33 thereof, past the valve 30 and will be discharged from the pipe or conduit 22 through the apertures or jets 25 in an outward and downward direction into the coal or burning embers, due to the fact that the inner end of the pipe 22 is closed as seen at 34. Sufficient air will thus be provided to produce proper combustion without other means of admitting air to the stove and as a result thereof no air will be admitted upwardly through the grate 19 thus reducing the tendency of the grate to oxidize, increasing the usable life of the grate. The concave upper side of the grate 19 tends to retain the coal and burning embers in close proximity to the air supply pipe 22 thus causing the coal to be burned more thoroughly and completely leaving less ash and reducing coal consumption. The valve 30 can be adjusted, as previously explained, to effectively and accurately control the burning of the fuel. By having the apertures 25 arranged to open outwardly and downwardly the air is not only better dispensed evenly through the coal and burning embers but the likelihood of the ashes accumulating in the apertures is greatly reduced.

Since the burning embers are concentrated in

the center of the grate 19, it is possible to employ a stove having a bottom and side wall formed of sheet metal which otherwise would only be adaptable for wood burning, so that by applying the attachment to conventional wood burning stoves of sheet metal the stove may be adapted for burning coal and similar fuel.

Various modifications and changes are contemplated and may obviously be resorted to without departing from the spirit and scope of the invention as hereinafter defined by the appended claim.

I claim:

15 A control valve for an air supply conduit of a stove, comprising a conduit provided with an arcuate circumferentially extending slot, said conduit having an upwardly projecting ear disposed adjacent an end of the slot, a valve body, an arm projecting radially from the valve body and pivotally connected to the ear, said arm extending through said slot for swingably supporting the valve body for movement through said slot into and out of the bore of the conduit, a handle projecting outwardly from said valve body and remote to said arm and disposed for movement in said slot for varying the position of the valve body with respect to the conduit bore, said valve body having a cut-away portion forming a restricted passage with a portion of the conduit, 20 when the valve is in a fully closed position, to insure the passage of a limited amount of air through the conduit at all times.

CURTIS T. STEVENS.
